UNITED STATES PATENT OFFICE.

JAKOB EMIL KIRBERG, OF PHILADELPHIA, PENNSYLVANIA, ASSIGNOR TO
THE HENSEL, COLLADAY COMPANY, OF PENNSYLVANIA.

DESIGN FOR TRIMMING.

SPECIFICATION forming part of Design No. 30,748, dated May 9, 1899.

Application filed April 14, 1899. Serial No. 713,060. Term of patent 14 years.

To all whom it may concern:

Be it known that I, JAKOB EMIL KIRBERG, a citizen of the United States, residing in the city and county of Philadelphia, State of Pennsylvania, have invented and produced a new and original Design for Trimming, of which the following is a specification, reference being had to the accompanying drawings, forming part thereof.

The leading feature of my design for trimming is a spiral tubular core and a spiral rim thereon.

Figure 1 represents a side elevation of a piece of trimming embodying my design. Fig. 2 represents a section thereof on line $x x$, Fig. 1.

In the drawings, A designates the body of the trimming, the same being composed of the tubular core B and the rim C. The core and rim are spiral in longitudinal direction. 20

Having thus described my invention, what I claim as new, and desire to secure by Letters Patent, is—

The design for trimming substantially as shown and described.

JAKOB EMIL KIRBERG.
